(57) CLAIM

The ornamental design for a bartop gaming console, as shown and described herein.

DESCRIPTION

FIG. 1 is a top view of a bartop gaming console of our new design.

FIG. 2 is a front view of the bartop gaming console of FIG. 1.

FIG. 3 is a left side view of the bartop gaming console of FIG. 1.

FIG. 4 is a right side view of the bartop gaming console of FIG. 1.

FIG. 5 is a rear view of the bartop gaming console of FIG. 1.

FIG. 6 is a bottom view of the bartop gaming console of FIG. 1.

FIG. 7 is a front perspective view of the bartop gaming console of FIG. 1; and,

FIG. 8 is a rear perspective view of the bartop gaming console of FIG. 1.

The broken lines are for the purpose of illustrating portions of the article that forms no part of the claimed design.
